E. MUELLER

ARCH SUPPORT

Filed Sept. 13, 1924

Inventor
E. Mueller,

By *Geo. Kimmel*
Attorney

UNITED STATES PATENT OFFICE.

ERNST MUELLER, OF ST. LOUIS, MISSOURI.

ARCH SUPPORT.

Application filed September 13, 1924. Serial No. 737,561.

To all whom it may concern:

Be it known that I, ERNST MUELLER, a citizen of the United States, residing in the city of St. Louis and State of Missouri, have invented certain new and useful Improvements in Arch Supports, of which the following is a specification.

This invention relates to arch supports, more particularly to an improvement upon the form of arch support as disclosed in Letters Patent #1,238,179, granted to me August 28, 1917, and not only embodying the objects and advantages as set forth in the Letters Patent referred to, but has for its further object to provide, in a manner as hereinafter set forth, an arch support having means to prevent the buckling or contracting of the support when worn, under such conditions overcoming any inconvenience to the user.

Further objects of the invention are to provide an arch support, in a manner herein-after set forth, which will afford relief to persons afflicted with weak ankles or with weak or broken arches, strong, durable, compact, thoroughly efficient and convenient in its use, and inexpensive to manufacture.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:—

Figure 1 is a perspective view of an arch support, in accordance with this invention.

Figure 2 is an inverted plan view.

Figure 3 is a side elevation, looking towards the other side of the support.

Figure 4 is a perspective view of the holding plate.

Referring to the drawings in detail, 1 denotes a foot supporting or engaging mem-

ber having one side edge and one end edge 50 bevelled, in a manner as disclosed in the Letters Patent referred to, and said member 1 has an intermediate portion 2 thereof flared or arched and said intermediate portion 2 which is flared or arched extends 55 from one side edge and terminates at a point removed from the other side edge of the member 1. The flared or arched intermediate portion 2 provides a symmetrical curve or arch to conform to the curvature of the 60 arch of the foot.

The member 1 is formed of flexible material, preferably leather, and to maintain the flared or arched shape intermediate portion 2 permanently in curved position, a 65 plurality of lifts or layers of flexible material are arranged in superposed relation against the lower face of the member 1 at the intermediate portion 2. The lifts or layers can be of any suitable number, and 70 as shown three are employed, as indicated by the reference characters 4, 5 and 6. The outer edges of the lifts or layers are bevelled so as to form a continuation of the bevelled side edge of the member 1. The 75 lifts or layers are further arranged in stepped relation.

Secured to the lower face of the member 1 is a segment shaped facing strip of flexible material, as indicated at 7, and which is secured in position by a row of stitching 8 which provides means for securing the strip 7 to the member 1. The strip 7 is of any suitable width and has its outer edge bevelled to conform to the bevelled outer edges of 80 the lifts or layers and also to the bevelled side edge of the member 1. The facing strip 1 maintains the lifts or layers in position with respect to the intermediate portion 2, for the purpose of maintaining the latter in 85 flared or arched position.

The construction described is substantially the same as that disclosed in the Letters Patent referred to and it has been found that without the employment of a holding or reinforcing means, the attaching member 1, from use, would buckle up or contract, making the arch support somewhat incon-

venient to the user. To prevent this contracting or buckling up, a metallic resilient holding plate is employed and which is secured against the lower face of the strip 7 and member 1. The said holding plate is generally indicated at 9 and is of compound curvature in longitudinal section. The plate 9 includes a wide portion 10 and a narrow portion 11 which are substantially of the same length.

The wide portion 10 is of a width less than the width of the member 1 and is positioned against the lower face of said member 1 at the rear end thereof, and said wide portion 10 conforms substantially in contour to the shape of the member 1 at the rear portion thereof.

The narrow portion 11 projects forwardly from the wide portion 10 and is of a width substantially half the width of the wide portion 10. The outer side edge of the narrow portion 11 forms a continuation of the outer side edge of the wide portion 10, and the forward edge of the wide portion 10 merges into the inner side edge of the narrow portion 11 centrally of the plate 9.

When the plate 9 is set up with respect to the member 1 and strip 7, the outer side edge of the plate 9 conforms to the shape of the outer side edge of the strip 7 and is substantially flush therewith.

The wide portion 10 of the plate 9, at the forward terminus thereof, is formed with an opening 12, and the narrow portion 11 at the forward terminus thereof is provided with an opening 13. The opening 12 is arranged approximately centrally of the plate 9, and the opening 13 is positioned approximately centrally of the narrow portion 11. Extending through the openings 12 and 13, as well as through the strip 7, lifts or layers 4, 5 and 6, and member 1, are hold-fast devices 14 in the form of rivets, which act as means for securing the plate 9 in position, as well as securing together the strip 7, lifts or layers, and member 1. The outer ends of the rivets are countersunk in the outer face of the member 1.

The rear of the wide portion 10 is free, forming a resilient end terminal for the plate 9 and which allows freedom for the rear end of the member 1, affording comfort when using the support and which will not interfere with any expansion to the rear end of the member 1, due to wear.

The arrangement of the plate 9 in the manner as illustrated and described, prevents any possibility of the intermediate portion 2 from buckling or contracting to an extent which cause a misfit or inconvenience to the user when the support is positioned with respect to the arch of the foot.

Although the preferred embodiment of the invention is as illustrated and described, yet it is to be understood that changes in the

details of construction can be had which will fall within the scope of the claims hereunto appended.

What I claim is:—

1. An arch support comprising a foot engaging member formed of nonmetallic material and provided with means intermediate its ends to constitute an arch supporting portion, a metallic holding plate opposing the lower face of said means and the lower face of said member at the rear end thereof, and means for securing said plate in position said plate including a wide part and a narrow part projecting forwardly from the wide part, and said securing means being arranged at the forward terminals of said parts.

2. An arch support comprising a foot engaging member formed of non-metallic material and provided with means intermediate its ends to constitute an arch supporting portion, a metallic holding plate opposing the lower face of said means and the lower face of said member at the rear end thereof, and means for securing said plate in position said plate having its outer side edge flush with the outer side edge of the means to provide the arch supporting portion, and said plate having its inner side edge spaced from the corresponding edge of said member.

3. An arch support comprising a foot engaging member formed of non-metallic material and provided with means intermediate its ends to constitute an arch supporting portion, a metallic holding plate opposing the lower face of said means and the lower face of said member at the rear thereof, a hold-fast device for securing said plate intermediate its ends to said means and member, and a hold-fast device for securing the forward end of said plate to said means and member, said plate consisting of a wide and a narrow part, said narrow part projecting forwardly from said wide part.

4. An arch support comprising a foot engaging member formed of non-metallic material and provided with means intermediate its ends to constitute an arch supporting portion, a metallic holding plate opposing the lower face of said means and the lower face of said member at the rear thereof, a hold-fast device for securing said plate intermediate its ends to said means and member, and a hold-fast device for securing the forward end of said plate to said means and member, said plate formed of a narrow and a wide part, said narrow part projecting forwardly from said wide part at one side thereof.

5. An arch support comprising a foot engaging member formed of non-metallic material and provided with means intermediate its ends to constitute an arch supporting portion, a metallic holding plate opposing the

lower face of said means and the lower face of said member at the rear thereof, a hold-fast device for securing said plate intermediate its ends to said means and member, 5 a hold-fast device for securing the forward end of said plate to said means and member, said plate formed of a narrow and a wide part, said narrow part projecting forwardly

from said narrow part at one side thereof, and said plate having its outer side edge 10 flush with said means and its other side edge spaced inwardly with respect to the corresponding edge of said member.

In testimony whereof, I affix my signature hereto.

ERNST MUELLER.
